Patented Aug. 17, 1976

241,038

LOUDSPEAKER CABINET OR SIMILAR ARTICLE

William T. Hibdon, 1212 W. Lill,
Chicago, Ill. 60614

Filed Nov. 17, 1975, Ser. No. 632,250

Term of patent 14 years

Int. Cl. D14—01

U.S. Cl. D14—01

FIG - 3

FIG - 1

FIG - 4

FIG - 2

FIG - 5

FIG. 1 is a perspective view of a loudspeaker cabinet or similar article, showing my new design;

FIG. 2 is a front elevational view thereof;

FIG. 3 is a top plan view and the bottom being a mirror image thereof;

FIG. 4 is a side elevational view thereof;

FIG. 5 is a rear elevational view thereof;

FIG. 6 is a perspective view of a second embodiment thereof; and

FIG. 7 is a perspective view of a third embodiment thereof.

I claim:

The ornamental design for a loudspeaker cabinet or similar article, as shown and described.
